UNITED STATES PATENT OFFICE.

JOHN H. WINDISCH, OF OAK HARBOR, OHIO.

REFRIGERATOR.

SPECIFICATION forming part of Letters Patent No. 399,307, dated March 12, 1889.

Application filed June 29, 1888. Serial No. 278,569. (No model.)

To all whom it may concern:

Be it known that I, JOHN H. WINDISCH, a citizen of the United States, residing at Oak Harbor, in the county of Ottawa and State of Ohio, have invented new and useful Improvements in Refrigerators, of which the following is a specification.

My invention relates to improvements in refrigerators, having for its object to provide a simple, cheap, and easily-operated device which may be placed in a cavity in the ground, and is designed to have vegetables, dairy products, and other articles which must be kept cool and out of contact with the air stored therein.

The invention consists in a certain novel construction and arrangement of devices fully set forth and claimed hereinafter in connection with the accompanying drawings, where-

20 in—

Figure 1 is a side view of a refrigerator embodying my improvements arranged in operative position in the ground. Fig. 2 is a vertical central sectional view of the same.

25 Referring by letter to the drawings, A designates the receiver, which may be of any preferred form, (preferably cylindrical,) and is arranged in a cavity in the ground with its upper edge projecting slightly above the surface thereof, and B B designate vertical standards, which are bolted at their lower ends to the diametrically-opposite sides of the receiver, and are provided at their upper ends with bearings b b, in which is 30 mounted the shaft C, having a crank, c. A hook, D, is mounted on one of the standards, and is adapted to engage the crank to hold it in any desired position.

E represents the elevator, which consists 40 of the parallel shelves F F, arranged at suitable distances apart, and the vertical straps, G G, which are affixed to the edges of the shelves and hold them in the desired position, and H represents a reservoir, which is 45 arranged between the upwardly-extending ends of the straps and is provided with the interior brackets, I I, on which rests the removable shelf or partition K, thereby forming a closed chamber, L, at the bottom of the 50 reservoir and an open chamber, M, above

the same. This reservoir fits sufficiently tightly in the upper end of the receiver and to prevent heat from passing in any considerable quantities to the interior of the receiver. The lower or closed chamber, L, of 55 the reservoir is filled with water, and the upper chamber is filled with sawdust, charcoal, or other similar non-conducting material. The straps G G project slightly above the upper edge of this reservoir, and the conical 60 cap N is affixed thereto and is adapted when the elevator is lowered into the receiver to close down tightly on the upper end of the latter, whereby insects, rain, &c., are excluded. Being conical in shape the water is prevented 65 from remaining on the cap N, and as its edges overlap or extend beyond the upper edges of the receiver the rain cannot penetrate between the cap and the edge of the receiver.

70 A chain or cord, O, is affixed to the center of the cap N, and is extended up and wound on a drum, P, at the center of the shaft C, whereby when it is desired to raise the elevator to obtain access to the contents of the 75 shelves thereof it is simply necessary to rotate the drum by means of the crank on the end of the shaft.

Inasmuch as the temperature of the earth below the surface is lower in summer than the 80 outside air, the interior of the receiver will be kept cool, and will thus preserve articles which are placed on the elevator below the non-conducting reservoir.

The shelves are preferably secured to the 85 vertical straps G G by means of small angle-irons f f, the arms f' f' of which are riveted or bolted respectively to the straps and the under sides of the shelves, and the cap N is secured to the upper ends of the said straps 90 by bending the straps inward and either bolting or riveting them thereto, as clearly shown in the drawings.

Having described my invention, I claim—
In a refrigerator, the combination, with the 95 receiver adapted to be arranged below the surface of the ground, of the elevator comprising the parallel shelves F F, held in position by the side straps, G G, the cap N, affixed to the upper ends of the straps and adapted 100

to fit over the upper end of the receiver when the elevator is lowered, and the reservoir H, arranged between the straps G, below the cap N, and provided with a removable shelf or partition, K, arranged on suitable brackets, II, whereby separated chambers L and M are formed, substantially as and for the purpose specified.

In testimony that I claim the foregoing as my own I have hereto affixed my signature in presence of two witnesses.

JOHN H. WINDISCH.
